[57] ABSTRACT

A device for compressing or expanding a number x having plural binary digits and belonging to a predetermined range of numbers representing the amplitude of a quantized signal, into a number y having a lower or higher number of binary digits following a nonlinear characteristic approximated by a series of straight line segments of varying slopes which divide the range of numbers into various groups of numbers including numbers of different amplitudes. The device comprises an input register for storing said number x ; and an output register for storing said number y , means for identifying the group to which the number x stored in the input register belongs, means for transferring predetermined binary digits relating to the level of the number x into such output register and means for storing into such output register binary digits relating to the identification of such group.

FIG. 3

PULSE CODE MODULATION DIGITAL COMPANDOR

This invention relates to a compressor-expander, more commonly known as a compandor for compressing or expanding a number having n binary digits into a number having a lower or higher number of binary digits.

In pulse code modulation systems (PCM), for example, a code containing a predetermined number of binary digits is used to transmit quantized values of an analog signal. As commonly known, the amplitude A of a quantized signal may only take a definite number of quantization steps the amplitude of which is hereinafter designated by character σ . In the PCM system when used for transmitting vocal signals, a ratio of 1,000 is generally accepted between the maximum and minimum amplitudes of a signal which may be transmitted. For this reason, the ratio A/σ has been chosen to be 1,024 or 2^{10} . Because of the positive and negative amplitudes of the analog signal, there will be 2,048 or 2^{11} quantization steps in quantized PCM system. However, such a value of σ is used for weak signals only and various compression laws where σ depends on the signal level permit to keep the quantized noise constant and acceptable by using only 2^7 quantization steps. As it is commonly known, the quantizing noise is caused by the quantizing error resulting from the difference between the instantaneous value of the analog signal and the quantized value of the same signal which is actually transmitted.

Up until now, the compression has been produced within the coder of the PCM system and various compressors have permitted to achieve coding of a signal directly from an analog form to a nonlinear digital form having 2^7 quantization steps. Similarly, the expanders of the prior art have permitted to pass directly from a nonlinear digital signal back into an analog signal.

It is therefore the main object of the invention to permit the compression of a digital signal which is coded linearly into a digital signal which is coded nonlinearly and vice versa.

A device for compressing or expanding a number x having plural binary digits into a number y having a higher or lower number of binary digits comprises:

- a. an input register having a number of storage elements for storing each of the binary digits of said x number;
- b. an output register having a number of storage elements for storing each of the binary digits of each y number;
- c. a first gate circuit in each group and responsive to predetermined combinations of binary digits in the storage elements of said input register for identifying the group to which said number x belongs;
- d. a second gate circuit in each group interconnecting predetermined storage elements of said input and output registers and responsive to said first gate circuit for transferring predetermined binary digits relating to the amplitude of said number x from said input register into said output register; and
- e. means responsive to said first gate circuit for storing into said output register binary digits relating to the identification of said group.

The invention will be further disclosed with reference to the accompanying drawings which illustrate a preferred embodiment of the invention and in which:

5 FIG. 1 illustrates a piecewise linear characteristic used for approximating the nonlinear characteristic of a compressor-expander in accordance with the invention wherein the scales are indicated by binary numbers but are nevertheless linear;

10 FIG. 2 illustrates the circuit diagram of a compressor; and

15 FIG. 3 illustrates the circuit diagram of an expander for performing the reverse operation of the compressor.

15 Referring to FIG. 1, the compression law which has been used in the digital compressor is as follows:

$$y = \ln(1 + \mu x) / \ln(1 + \mu)$$

wherein y = output signal,

20 x = input signal, and μ is a constant, for example, $\mu = 100$.

The curve obtained in following this law is approached by six straight line segments as illustrated. However, it is to be understood that any other compression law could be used.

25 It is possible to code the amplitude of an analog signal in two ways:

1. the level varies between 0 and $+2A$ and the quantization steps are numbered 1 to 2^n using a number having n binary digits;
2. the level varies between $+A$ and $-A$ and the quantization steps are characterized by a number having $n-1$ binary digits representing the amplitude and an extra binary digit representing the sign (+ or -) of such amplitude.

The second solution has been retained because it requires less equipment. In FIG. 1, it is only necessary to determine to which group, among six different groups (segments), the binary number belongs and what is its sign. This only requires $6 + 1 = 7$ identification circuits. On the contrary, the first solution would have required to determine to which group, among 11 groups, the binary number belongs.

In the Cartesian coordinate system of FIG. 1, the binary code shown plotted below the X axis corresponds to analog values which are shown immediately above the X axis. Thus if the binary digits were converted to analog values in a conventional linear digital to analog converter, with $2^0 = 1$, the resulting analog values would form a first series of linear analog values which are plotted on the X axis. Similarly a second series of analog values would result from the conversion of the output binary digits in a linear digital to analog converter and this second series of analog values is plotted on the Y axis together with the corresponding digital code. When the first and second series are plotted on the Cartesian coordinate system the resulting series of points define a plurality of straight line segments connected together by breakpoint. These straight line segments, shown in FIG. 1, are an approximation to a logarithmic function such as defined above. In practice the maximum values of x and y are unity so that the values shown on the X and Y axes would be normalized to one.

It is therefore necessary to transform a number x having 10 binary digits (the 11th digit being the sign)

into a number y having six binary digits (the seventh digit being the sign). The coordinates of the extremities of the segments are as follows expressed in a system using binary numbers:

$x =$	$0 0 0 0 0 0 0 0 0 0 0 0$	$y =$	$0 0 0 0 0$
	1 0 0 0 0		1 0 0 0 0
	1 0 0 0 0 0		1 1 0 0 0
	1 0 0 0 0 0 0		1 1 0 0 0 0
	1 0 0 0 0 0 0 0		1 1 0 0 0 0 0
	1 0 0 0 0 0 0 0 0		1 1 1 0 0 0 0
	1 0 0 0 0 0 0 0 0 0		1 0 0 0 0 0 0

However, to facilitate the distinction of the groups, eight groups have been formed as illustrated in the following Table 1 by breaking the third and fourth segments into two segments each.

TABLE 1

Intervals

Group Number	x element from	y element from
I	0,	111
II	1000,	1111
III	10000,	11111
IV	100000,	111111
V	1000000,	1111111
VI	10000000,	11111111
VII	100000000,	111111111
VIII	1000000000,	1111111111

The equations of the eight segments expressed in binary numbers are as follows:

Equations of Segments

Group Number	Group Number
I $y = x$	II $y = x/10 + 100$
III $y = x/100 + 1000$	IV $y = x/1000 + 10000$
V $y = x/10000 + 100000$	VI $y = x/100000 + 1000000$
VII $y = x/1000000 + 10000000$	VIII $y = x/10000000 + 1100000$

Referring to the above equations, it may be seen that the slopes of the various segments are: 1, 1/10, 1/100, 1/1000, 1/10,000, 1/1,000,000.

It is to be noted that the numbers in each group before and after transformation consists of one or plural group identification digits and of plural digits which indicate the level of the number in each group. For example, if the binary digits are numbered x_9 to x_0 in the order of their decreasing weights, a number x in group II is composed of seven group identification digits (0000001) and of three digits indicating the level of the number in each group (x_2, x_1, x_0). The transformation of x in this group II is $y = (x/10) + 100$ which consists of four group identification digits (y_5 to y_2 : 0010) and two digits indicating the level in the group. This may be represented by the following equation:

$$x = 0000001x_2x_1x_0, y = 0010x_2x_1.$$

Using the same convention, the transformation in the eight groups will be as follows:

Group I	$x = 0 0 0 0 0 0 0 x_2 x_1 x_0$	$y = 0 0 0 x_2 x_1 x_0$
II	$x = 0 0 0 0 0 0 1 x_2 x_1 x_0$	$y = 0 0 1 0 x_2 x_1$
III	$x = 0 0 0 0 0 1 x_2 x_1 x_0$	$y = 0 0 1 1 x_3 x_2$
IV	$x = 0 0 0 0 1 x_2 x_3 x_2 x_1 x_0$	$y = 0 1 0 x_4 x_3 x_2$
V	$x = 0 0 0 1 x_2 x_3 x_4 x_2 x_1 x_0$	$y = 0 1 1 x_5 x_4 x_3$
VI	$x = 0 1 x_2 x_3 x_4 x_5 x_2 x_1 x_0$	$y = 1 0 x_6 x_5 x_4 x_3$
VII	$x = 1 x_2 x_3 x_4 x_5 x_6 x_2 x_1 x_0$	$y = 1 1 0 x_7 x_6 x_5$
VIII	$x = 1 x_2 x_3 x_4 x_5 x_6 x_7 x_2 x_1 x_0$	$y = 1 1 1 x_8 x_7 x_6$

The transfer of a number in each of groups I-VIII from 10 to six binary elements is illustrated in the following Table 2 wherein the "0" have been eliminated.

TABLE 2

Binary Element Number	Group Number							
	I	II	III	IV	V	VI	VII	VIII
10	1	x_0	x_1	x_2	x_3	x_4	x_5	x_6
	2	x_1	x_2	x_3	x_4	x_5	x_6	x_7
	3	x_2	$x_4 = 1$	x_4	x_5	x_6	x_7	x_8
	4		1	1	$x_6 = 1$	x_6		1
	5				1		1	
	6					1	1	1

Table 2 mentioned above suggest a method for effecting the transformation. It will be necessary to:

1. identify the group to which x belongs (for example, 0000001 $x_2x_1x_0$ is a number in group II);
2. transfer the useful 2, 3 or 4 x_i in a register having six positions;
3. store in the register the group identification digits.

The above-mentioned operations 2 and 3 may be effected simultaneously. If the six position register is empty before transferring any numbers into it, Table 2 indicates the elements to be placed in it.

The identification logic functions of each of the groups are:

I	$G_1 = \bar{x}_9\bar{x}_8\bar{x}_7\bar{x}_6\bar{x}_5\bar{x}_4\bar{x}_3$
II	$G_2 = \bar{x}_9\bar{x}_8\bar{x}_7\bar{x}_6\bar{x}_5\bar{x}_4x_3$
III	$G_3 = \bar{x}_9\bar{x}_8\bar{x}_7\bar{x}_6\bar{x}_5x_4x_3$
IV	$G_4 = \bar{x}_9\bar{x}_8\bar{x}_7x_6x_5$
V	$G_5 = \bar{x}_9\bar{x}_8\bar{x}_7x_6$
VI	$G_6 = x_9x_8x_7$
VII	$G_7 = \bar{x}_9x_8$
VIII	$G_8 = x_9$

FIG. 2 illustrates an electrical diagram of the transfer circuits required for all the groups of numbers to effectuate the transformation of Table 2. Such transfer circuits include AND gates A₁ to A₂₅ and OR gates 0₁ to 0₈.

Taking the groups separately in consecutive order, it will be seen that a number in group I the identification digits $x_9 x_8 x_7 x_6 x_5 x_4$ of which are equal to 0 0 0 0 0 0 will permit gate A₄ to conduct to provide a digital output "1" to the first input of gates A₁, A₂, and A₃ to permit such gates to transfer binary digits x_0, x_1 and x_2 stored in the input register 10 of the compressor into the proper storage elements y_0, y_1 and y_2 of the output register 11 of the compressor through OR gates 0₁ to 0₃ in accordance with the above-mentioned Table 2.

The group identification digits of a number in group II having the form 0 0 0 0 0 0 1 will render gate A₇ conductive and thereby apply a digital signal "1" to the first input of gates A₅ and A₆, thus causing the transfer of binary digits x_1 and x_2 from the input register of the compressor into the proper storage elements y_0 and y_1 of the output register through the second input of OR gates 0₁ and 0₂.

A number in group III having the following identification digits 0 0 0 0 0 1 will render gate A₁₁ conductive and apply a digital signal "1" to the first input of gates A₈, A₉ and A₁₀ through OR gate 0₄, thus causing the transfer of digit x_2, x_3 and x_4 of the input register of the compressor into the proper storage elements y_0, y_1 and

y_2 of the output register thereof through the OR gates 0_1 to 0_3 .

A number in group IV having the following identification digits 0 0 0 0 1 will render gate A_{12} conductive and thus apply a digital input "1" to gates A_8 , A_9 and A_{10} , thus causing the transfer of digits x_2 , x_3 and x_4 in the input register of the compressor into the storage elements y_0 , y_1 and y_2 of the output register. It will be noted that the identification digits of groups III and IV are both applied through OR gate 0_4 to the same transfer gates A_8 , A_9 and A_{10} . Indeed, x_2 , x_3 and x_4 must be transferred into storage elements y_0 , y_1 and y_2 in both groups, the only difference being that $x_4 = 1$ in group III.

A number in group V having the following identification digits 0 0 0 1 will render gate A_{17} conductive and thus apply a digital signal "1" to the first input of gates A_{13} to A_{16} through OR gate 0_5 , thus transferring digits x_3 , x_4 , x_5 and x_6 in the input register of the compressor into the storage elements y_0 , y_1 , y_2 and y_3 of the output register of the compressor. The output of AND gates A_{13} , A_{14} and A_{15} is applied to the register through OR gates 0_1 , 0_2 and 0_3 respectively.

A number in group VI having the identification digits 0 0 1 will render gate A_{18} conductive thus transferring digits x_3 , x_4 , x_5 and x_6 into storage elements y_0 , y_1 , y_2 and y_3 . It will be noted that the output of gates A_{17} and A_{18} are both applied through OR gate 0_5 to gates A_{13} to A_{16} . This is because the same digits x_3 , x_4 , x_5 and x_6 are to be transferred into storage elements y_0 , y_1 , y_2 and y_3 in both groups V and VI except that in group V, $x_6 = 1$.

An element in group VII having the following identification digits 0 1 will render gate A_{22} conductive thus applying a digital signal "1" to gates A_{19} , A_{20} and A_{21} and transferring digits x_5 , x_6 and x_7 into the storage elements y_0 , y_1 and y_2 through the OR gates 0_1 to 0_3 .

A number in group VIII having the identification digit 1 will apply a digital signal 37 1" to gates A_{23} , A_{24} and A_{25} thus transferring digits x_6 , x_7 and x_8 into the storage elements y_0 , y_1 and y_2 .

FIG. 2 also illustrates the storage of the identification digits for each of the groups I to VIII. There is shown an OR gate 0_6 to which is applied the signals G_2 , G_3 and G_8 , an OR gate 0_7 , to which is applied the identification signals G_4 , G_5 , G_7 and G_8 , and OR gate 0_8 to which is applied the identification signals G_6 , G_7 and G_8 , such identification signals being also illustrated in FIG. 2. One of the identification signals G_1 to G_8 becomes equal to 1 when a number pertaining to a predetermined group occurs while the remaining identification signals remain equal to zero. For example, a number in group I causes G_1 alone to be equal to 1 and, consequently, digits y_3 , y_4 and y_5 in the storage elements of the output register remain equal to zero.

A number in group II causes a digit 1 to be applied to OR gate 0_6 to change the state of y_3 into the state 1 while y_2 , y_4 and y_5 remain in the state zero.

A number in group III causes a digit $y_3 = 1$ to be stored in the output register while y_4 and y_5 remain equal to zero. In addition, a digit 1 is stored in storage element y_2 .

A number in group IV causes a digit 1 to be applied to OR gate 0_7 to change the state of y_4 into the state 1 while y_3 and y_5 remain equal to zero.

A number in group V causes a digit 1 to be applied to OR gate 0_7 to change the state of y_4 into state 1 while y_5 remains equal to 0. In addition, a digit 1 is stored into storage element y_3 .

An element in group VI causes a signal 1 to be applied to OR gate 0_8 to change the state of y_5 into state 1 while y_4 remains equal to zero.

An element in group VII causes a digit 1 to be applied to both OR gates 0_7 and 0_8 thus changing the states of y_4 and y_5 into state 1 while y_3 remains equal to zero.

An element in group VIII causes a digit 1 to be applied to OR gates 0_6 , 0_7 and 0_8 to change the state of y_3 , y_4 and y_5 into state 1.

The purpose of the digital expander is to transform a signal having seven binary elements back into a signal having 11 binary elements in which σ is constant for all amplitudes of the signal. The compression law is opposite to that of the compressor, that is if y is the input number having six binary elements, x , the output number, will have 10 binary elements. The equations are as follows:

Group	I	$y = 0\ 0\ 0\ y_2\ y_1\ y_0$	$x = 0\ 0\ 0\ 0\ 0\ 0\ 0\ y_2\ y_1\ y_0$
II	$y = 0\ 0\ 1\ 0\ y_1\ y_0$	$x = 0\ 0\ 0\ 0\ 0\ 0\ 1\ y_1\ y_0\ 0$	
III	$y = 0\ 0\ 1\ 1\ y_1\ y_0$	$x = 0\ 0\ 0\ 0\ 0\ 1\ y_1\ y_0\ 0\ 0$	
IV	$y = 0\ 1\ 0\ y_2\ y_1\ y_0$	$x = 0\ 0\ 0\ 0\ 1\ y_2\ y_1\ y_0\ 0\ 0$	
V	$y = 0\ 1\ 1\ y_2\ y_1\ y_0$	$x = 0\ 0\ 0\ 1\ y_2\ y_1\ y_0\ 0\ 0\ 0$	
VI	$y = 1\ 0\ y_3\ y_2\ y_1\ y_0$	$x = 0\ 0\ 1\ y_3\ y_2\ y_1\ y_0\ 0\ 0\ 0\ 0$	
VII	$y = 1\ 1\ 1\ y_2\ y_1\ y_0$	$x = 0\ 1\ y_2\ y_1\ y_0\ 0\ 0\ 0\ 0\ 0\ 0$	
VIII	$y = 1\ 1\ 1\ y_2\ y_1\ y_0$	$x = 1\ y_2\ y_1\ y_0\ 0\ 0\ 0\ 0\ 0\ 0\ 0$	

The transformation method is the same as for the compressor. If the ten position register is empty before the transfer, the following Table 3 indicates the elements to be placed into it.

TABLE 3

Binary element number	Group Number							
	I	II	III	IV	V	VI	VII	VIII
1	y_0							
2	y_1	y_0						
3	y_2	y_1	y_0		y_0			
4		y_1		y_1		y_0	y_1	
5			$y_2 = "1"$		y_2		y_1	y_1
6				$y_2 = "1"$		y_2	y_2	y_0
7					$y_3 = "1"$	y_3	y_1	y_0
8							y_2	y_1
9								y_2
10								1

The identification logic functions of each of the groups are:

I	$C_1 = \bar{y}_3\ \bar{y}_4\ \bar{y}_5$
II	$C_2 = \bar{y}_3\ \bar{y}_4\ y_5\ \bar{y}_2$
III	$C_3 = y_3\ y_4\ y_5\ y_2$
IV	$C_4 = \bar{y}_5\ y_4\ \bar{y}_3$
V	$C_5 = \bar{y}_5\ y_4\ y_3$
VI	$C_6 = y_5\ \bar{y}_4$
VII	$C_7 = y_5\ y_4\ \bar{y}_3$
VIII	$C_8 = y_5\ y_4\ y_3$

FIG. 3 illustrates the transfer circuits of the expander including AND gates A_{30} to A_{35} and OR gates 0_{10} to 0_{19} .

A number in Group I the identification digits y_5 y_4 y_3 of which are 0 0 0 will render gate A_{33} conductive and apply a digital signal 1 to AND gates A_{30} , A_{31} and A_{32} .

thus transferring digits y_0 , y_1 and y_2 of the input register 20 of the expander into the storage elements x_0 , x_1 and x_2 of the output register 21 of the expander. The output of AND gates A_{31} and A_{32} is applied to the first input of OR gates 0_{10} and 0_{11} respectively.

An element in group II the identification digits y_5 , y_4 , y_3 , y_2 of which are 0 0 1 0 will render gate A_{36} conductive thus applying a digital signal 1 to gates A_{34} and A_{35} to transfer digits y_0 and y_1 into storage elements x_1 and x_2 through the second input of gates 0_{10} and 0_{11} .

A number in group III the identification digits y_5 , y_4 , y_3 , y_2 of which are 0 0 1 1 will render gate A_{40} conductive thus applying a digital signal 1 to gates A_{37} , A_{38} and A_{39} through OR gate 0_{18} to transfer digits y_0 , y_1 and y_2 into storage elements x_2 , x_3 and x_4 . The output of AND gates A_{37} to A_{39} is applied to the output register 21 through the appropriate inputs of OR gates 0_{11} to 0_{13} .

An element in group IV the identification digits of which are 0 1 0 will render gate A_{41} conductive thus applying a digital signal 1 to gates A_{37} , A_{38} and A_{39} and transferring digits y_0 , y_1 and y_2 into storage elements x_2 , x_3 and x_4 . It is to be noted that the identification of both groups III and IV is performed by the same transfer circuit through OR gate 0_{18} . It is because the same digits y_0 , y_1 and y_2 are transferred in both groups except that for group III, $y_2 = 1$.

A number in group V having identification digits 0 1 1 will render gate A_{46} conductive thus applying a digital signal 1 to gates A_{42} to A_{45} through OR gate 0_{19} to transfer digits y_0 , y_1 , y_2 and y_3 into storage elements x_3 , x_4 , x_5 and x_6 through OR gates 0_{12} to 0_{15} respectively.

An element in group VI having identification digits 10 will render gate A_{47} conductive thus applying a digital signal 1 to gates A_{42} to A_{45} and transferring digits y_0 , y_1 , y_2 and y_3 into storage elements x_3 , x_4 , x_5 and x_6 . It is to be noted that groups V and VI use the same transfer circuit because in both groups the same digits y_0 , y_1 , y_2 and y_3 are to be transferred into x_3 , x_4 , x_5 and x_6 except that $y_3 = 1$ in group V.

An element in group VII having identification digits 1 1 0 will render gate A_{51} conductive thus applying a digital signal 1 to gates A_{48} to A_{50} and transferring digits y_0 , y_1 and y_2 into storage elements x_5 , x_6 and x_7 through the appropriate inputs of OR gates 0_{14} to 0_{16} .

An element in group VIII having identification digits 1 1 1 will render gate A_{55} conductive thus applying a digital signal 1 to gates A_{52} to A_{54} and transferring digits y_0 , y_1 and y_2 into storage elements x_6 , x_7 and x_8 through the appropriate inputs of OR gates 0_{15} to 0_{17} .

The storage of the group identification digits is as follows:

- a. a number in group I leaves storage elements x_3 to x_9 unchanged and thus equal to zero;
- b. a number in group II stores a digit 1 in storage element x_3 while x_4 to x_9 remain equal to zero;
- c. a number in group III stores a digit 1 in storage element x_4 while leaving storage elements x_5 to x_9 equal to zero;
- d. a number in group IV stores a digit 1 in storage element x_5 , while leaving storage elements x_6 to x_9 unchanged;
- e. a number in group V stores a digit 1 in storage element x_6 while leaving storage elements x_7 to x_9 unchanged;

- f. a number in group VI will store a digit 1 in storage element x_7 while leaving storage elements x_8 and x_9 unchanged;
- g. a number in group VII will store a digit 1 in x_8 while leaving x_9 unchanged;
- h. a number in group VIII will store a digit 1 in storage element x_9 .

Although the above described compressor-expander has been disclosed for use with a PCM system using a seven digit code, it is to be understood that it could be used in any system requiring compression or expansion of a binary number having any number of digits into a second number having a lower or higher number of digits.

We claim:

1. A device for parallel conversion of m digit coded signals to n digit coded signals, $m \neq n$, wherein the m digit coded signals are such that when converted to analog in a linear digital to analog converter produce a first series of analog output values and the n digit coded signals are such that when converted to analog in a linear digital to analog converter produce a second series of analog output values and wherein a plot of said 1st series on the X axis and the 2nd series on the Y axis of a Cartesian coordinate system, produces a locus of points defining a plurality of successive straight line segments each having a different slope and connected to one another at breakpoints, said line segments extending from different lower absolute analog values to different higher absolute analog values and approximating a logarithmic function of x substantially described by

$$f(x) = Y = \ln(1+Cx)/\ln(1+C)$$

where C is a constant, wherein more significant digits of said coded signals correspond to analog values associated with and identifying said breakpoints and less significant digits of said coded signals correspond to analog values associated with the position on said line segment which has the identified breakpoint corresponding to its lowest absolute analog values, comprising:

1. an input register having a plurality of storage elements for storing the m digit coded signal,
2. an output register having a plurality of storage elements for storing the n digit coded signal,
3. a plurality of first gate circuit means equal at least to the number of straight line segments for connecting predetermined input storage elements to predetermined output storage elements, said plurality of first gate circuit means being responsive to the most significant activated digit of the m digit coded signal for identifying the breakpoint of said line segments, and
4. a plurality of second gate circuit means each responsive to one of said first gate circuit means and to digits less significant than the said significant digit of the m digit coded signal for connecting predetermined input storage elements to predetermined output storage elements for identifying the position along the straight line segment having the identified breakpoint which breakpoint corresponds to the lowest equivalent absolute analog values of the particular segment.

2. A device as recited in claim 1 wherein line segment breakpoints are identified by the logic functions:

9

$$\begin{aligned}
 f(1) &= \overline{X}_{m-1} \overline{X}_{m-2} \overline{X}_{m-3} \dots \overline{X}_{m-k} \\
 f(2) &= \overline{X}_{m-1} \overline{X}_{m-2} \overline{X}_{m-3} \dots \overline{X}_{m-k-1} X_{m-k} \\
 f(3) &= \overline{X}_{m-1} \overline{X}_{m-2} \overline{X}_{m-3} \dots \overline{X}_{m-k-2} X_{m-k-1} \\
 f(P-1) &= \overline{X}_{m-1} X_{m-2} \\
 f(P) &= X_{m-1}
 \end{aligned}$$

where $\overline{X}$ represents the opposite binary state as X ; $m-k-1$ is an integer greater than zero; $k-1$ is a positive integer less than m ; and P is a positive integer greater than one.

3. A device as recited in claim 1 wherein line segment breakpoints are identified by the logic functions:

$$\begin{aligned}
 f(1) &= \overline{X}_9 X_8 \overline{X}_7 X_6 X_5 \overline{X}_4 X_3 \\
 f(2) &= \overline{X}_9 X_8 X_7 X_6 X_5 \overline{X}_4 X_3 \\
 f(3) &= \overline{X}_9 \overline{X}_8 X_7 X_6 X_5 X_4 \\
 f(4) &= \overline{X}_9 X_8 X_7 X_6 X_5 \\
 f(5) &= \overline{X}_9 \overline{X}_8 \overline{X}_7 X_6
 \end{aligned}$$

10

$$\begin{aligned}
 f(6) &= \overline{X}_9 \overline{X}_8 X_7 \\
 f(7) &= \overline{X}_9 X_8 \\
 f(8) &= X_9
 \end{aligned}$$

wherein $\overline{X}$ represents the opposite binary state as X .

4. A device as recited in claim 1 wherein line segment breakpoints are identified by the logic functions:

$$\begin{aligned}
 f(1) &= \overline{Y}_5 Y_4 \overline{Y}_3 \\
 f(2) &= \overline{Y}_5 \overline{Y}_4 Y_3 \overline{Y}_2 \\
 f(3) &= \overline{Y}_5 \overline{Y}_4 Y_3 Y_2 \\
 f(4) &= \overline{Y}_5 Y_4 \overline{Y}_3 \\
 f(5) &= \overline{Y}_5 Y_4 Y_3 \\
 f(6) &= Y_5 \overline{Y}_4 \\
 f(7) &= Y_5 Y_4 \overline{Y}_3 \\
 f(8) &= Y_5 Y_4 Y_3
 \end{aligned}$$

15 wherein $\overline{Y}$ represents the opposite binary state as Y .
